SPACE DISCHARGE TUBE HAVING A NEGATIVE RESISTANCE CHARACTERISTIC

August Hund, West Orange, N. J., assignor to
Wired Radio, Inc., New York, N. Y., a corpora-
tion of Delaware

Application April 5, 1932, Serial No. 603,284

2 Claims. (Cl. 250—36)

This invention relates to electrical discharge tubes and more particularly to gaseous tubes in which upon setting up a glow discharge therein a negative resistance characteristic is exhibited.

5 An object of my invention is to provide an electrical discharge tube of this character comprising a plurality of electrodes surrounded by a gas at an attenuated pressure, two of which electrodes may be characterized as ionization electrodes while at least one additional electrode is included in a "work" circuit, the voltage of which may be adjusted independently of the ionizing voltage.

10 Another object of my invention is to provide a tube of the class described which functions so as to exhibit a negative resistance characteristic, thereby rendering it useful in a variety of different circuits such as, for example, in an oscillator or an amplifier.

15 Another object of my invention is to provide a tube of the class described in which the electrodes are of suitable formation and so arranged with respect to one another that the optimum conditions may be obtained for exhibiting the negative resistance characteristic of such a tube.

20 In my copending application Serial No. 573,076 filed November 5, 1931, the theory of operation of gaseous discharge tubes to exhibit a negative resistance characteristic was expounded in detail. In that application, however, tubes having only two electrodes were shown.

25 In my copending application Serial No. 590,561 filed February 3, 1932 I have described gaseous discharge tubes having a plurality of at least four electrodes. In that application I have mentioned the fact that under certain conditions such tubes may exhibit a negative resistance characteristic. The exhibition of a negative resistance characteristic is not, however, relied upon for producing the desirable results for which the several species of invention shown in Serial 590,561 are intended.

30 This invention may, therefore, be distinguished from those which are disclosed in the above cited copending applications in the following particulars:

35 By means of the separate ionizing electrodes as herein described it is possible to produce a degree of ionization such that undesirable relaxation variations may be avoided in the work circuit and the negative resistance reaction produced in the latter can be extended over a much wider working range than would be possible, say, with tubes having only two electrodes.

40 45 50 55 55 These and other advantages will be more fully

understood from the following description and by reference to the accompanying drawing in which:

Fig. 1 depicts one form of an electrical discharge tube having two electrodes in an ionizing circuit and two other electrodes in an oscillator circuit which exhibits a negative resistance characteristic;

5 Fig. 2 is a modification of the tubes of my invention showing only three electrodes of suitable formation, one of which, namely the cylindrical electrode, serves a double purpose because it is comprehended in the two circuits for ionization and for the oscillatory output respectively; and

10 Fig. 3 is another modification of my invention showing electrodes of suitable formation to act as an amplifier having a negative resistance characteristic.

15 The discharge tubes of this invention are capable of modification in many respects. The relative sizes and shapes of the electrodes as well as the kind and pressure of gas in which they are enveloped may be varied within wide limits in order to obtain the desired results. 20 The essential feature, however, is the presence of a very pronounced negative resistance characteristic in the tube itself. It has been shown that with this negative resistance characteristic the tube functions very satisfactorily either as an oscillator or as an amplifier.

25 In the herein described embodiments of my invention I use at least three, and, in some cases, preferably, a greater number of electrodes. The voltage required for ionization and the voltage applied in the work circuit may be adjusted independently of one another. Furthermore, the protective resistance which is necessary in the ionization circuit and which is undesirable in the work circuit can be so disposed as to render the 30 35 40 45 50 55 60 65 70 75 80 85 90 95 100 tube highly efficient in its operation.

75 Referring now to Fig. 1, a four-element tube is shown and in connection therewith, for illustrative purposes, an oscillator network appears. 45 Outwardly the tube may be of conventional type having a base 1, an envelope 2, and prongs 3. The ionization cathode 4 and ionization anode 5 are placed in a circuit which includes the source of potential 6 and the protective resistance 7. 50 The network upon which oscillations may be generated includes an anode 8 and a cylindrical cathode 9, the latter preferably surrounding all of the other electrodes. Each of the electrodes is supported by an insulated post, preferably of 55 60 65 70 75 80 85 90 95 100

glass, in order that ionization may not take place between the leads.

A suitable difference of potential may be applied between the anode 8 and cathode 9 by means of a battery 10 which is isolated from the oscillatory currents generated in the network, use being made of one or more choke coils 11. A resistance 12 may also be used to adjust the voltage across the electrodes 8 and 9. In shunt with the work electrodes 8 and 9 is an oscillator network comprising an adjustable condenser 13 in parallel with the primary inductance of a transformer 14, this parallel combination being in series with a condenser 15. The condenser 15 serves to prevent a flow of direct current from the battery 10 through the primary coil of the transformer 14.

The operation of this oscillator system is as follows: Oscillations will be set up in a well-known manner in the shunt branch when a negative resistance action takes place between the electrodes 8 and 9. This is due to the fact that the negative resistance permits power to be supplied to the condenser with a periodicity depending upon the charge and discharge rate of the condenser 13 in association with the transformer 14 as shown. In order to suitably adjust all of the factors entering into the operation of this oscillator system it will be understood that any desired frequency may be obtained upon adjustment of the elements 13, 14 and 15 with respect to the values of the negative resistance. The limiting values of the latter are determined by choosing a suitable current in the work circuit, which in turn is derived from the selection of a proper voltage of the source 10 and the adjustment of the tap along the resistance 12.

Referring now to Fig. 2, another oscillator circuit is shown in connection with a modified form 40 of the tube of my invention. This tube comprises an electrode 9a which serves the double purpose of an anode in the ionizing circuit and a cathode in the work circuit. This electrode is preferably of cylindrical or cup-shaped formation. The ionizing circuit includes the source of potential 6, a choke coil 16, the electrodes 9a and 4 and the protective resistance 7. The oscillator network of Fig. 2 differs from that of Fig. 1 chiefly as regards the arrangement of 45 the adjustable condenser 17 which is placed in series with the primary of the output transformer 14. The necessity for an additional condenser such as condenser 15 in Fig. 1 is thereby avoided. The source of potential 10a is connected on the 50 negative side through the choke coil 16 to the electrode 9a. Another choke coil 18, and, if desired, a resistance 12 in series therewith may be connected between the positive pole of the battery 10a and the work anode 8.

From what has been said with regard to the operation of the tube of Fig. 1 as an oscillator the corresponding manner of operation of the tube and network of Fig. 2 will be readily understood by those skilled in the art.

Referring now to Fig. 3, another modification 65 of my invention is shown comprising a three-element tube. The ionizing electrodes of this tube comprise preferably a small solid cylindrical anode 19 and a surrounding cathode 9b of hollow cylindrical formation. The latter electrode also acts in cooperation with the tip shaped anode 8 to produce a negative resistance reaction in the work circuit.

The tube of Fig. 3 may be used as an amplifier but this use will be understood to be merely

illustrative of a variety of purposes to which it is adapted. The electrodes may also be varied somewhat in their structure.

In order that suitable potentials may be applied between the several electrodes, I find it convenient to use a potentiometer 20, to the negative end of which the electrode 9b may be connected. The ionizing circuit for this tube includes the source of potential 21, the protective resistance 7, the ionizing anode 19, and electrode 10 9b, which in this circuit acts as a cathode and which is connected to the negative side of the source 21. Between the work circuit anode 8 and the electrode 9b may be connected an amplifier network including the secondary of an 15 input transformer 22 in series with which is an ordinary resistance 24 and a condenser 25.

The output of this network is derived from differences of potential across the resistance 24. Since the latter is in series with the negative 20 resistance of the tube and since amplified variations are produced across the resistance 24 with respect to the input voltage generated in transformer 22 it will be seen that a favorable degree of amplification takes place in the output branch 25 23. The negative resistance action in this case is the same as was explained in my copending application Serial 573,076.

If desired, the amplifier network may be readily modified by those skilled in the art so 30 as to obtain a current amplification as distinguished from voltage amplification.

The output branch 23 includes a condenser 27 for preventing the flow of direct current therethrough. The condenser 25 bypasses the useful variable current around the resistance of the potentiometer 20. The proper voltage may thus be applied to the electrodes 8 and 9b through the adjustable tap 26 on the potentiometer 20 without offering too great an impedance in the potentiometer to the variable currents.

In carrying out my invention it will be understood that a wide degree of variation in the construction of the tubes is permissible. A particular tube which I have tested was found to give satisfactory results and to produce a negative resistance that could be varied from about 1000 ohms to about 100,000 ohms. This tube happened to be filled with helium to a pressure 50 of about 15 mm. Argon is particularly suitable for negative resistance work. I have used other gases, however, and with pressures as great as 150 mm. The ionizing current of the tube that was tested was about 20 milliamperes while the 55 work circuit current was in the neighborhood of 6 milliamperes. The voltage was taken from a battery eliminator, about 500 volts being applied in the ionizing branch and about 150 volts were impressed on the work circuit. Stability of 60 operation was obtained by proper adjustment of the values of the protective resistance 7 and the adjustment of the potentiometer 20 or the resistance 12. The values herein stated for the tube under test are not in any way to be considered as important or critical. Neither do I 65 wish to limit myself to the three species of my invention herein illustrated. It will be understood that a wide variety of modifications of tubes exhibiting a negative resistance characteristic is possible. My invention, therefore, is limited only in accordance with the scope of the appended claims.

I claim:

1. In a space discharge tube system compris- 75

- ing, an envelope having an attenuated gaseous atmosphere therein and a plurality of electrodes, means including certain of said electrodes for producing therebetween a region of electrical stress for causing a corresponding region of primary gaseous ionization between said electrodes, means including certain of said electrodes for producing therebetween another region of electrical stress for causing between said electrodes a secondary region of gaseous ionization, one of said electrodes being formed to substantially enclose said primary and secondary regions of ionization in order that said primary region of ionization may exert a controlling effect upon said secondary ionization whereby a pronounced negative resistance characteristic is exhibited by said tube and relaxation oscillations are avoided.
2. In a space discharge tube system including, an envelope enclosing an attenuated gaseous atmosphere and a plurality of electrodes, means for causing certain of said electrodes to produce between said electrodes a region of electrical stress to produce therebetween a corresponding region of primary ionization, said means including an external primary ionization circuit having a source of voltage and a resistance therein and means for causing certain of said electrodes to produce therebetween another region of electrical stress to set up a secondary region of ionization between said electrodes, said means including a work circuit having a source of voltage connected therein, one of said electrodes being formed to substantially enclose said primary and secondary regions of ionization to permit said primary ionization to control said secondary ionization to produce a negative resistance characteristic for said tube and inhibit the generation of relaxation oscillations.

AUGUST HUND. 20
